UNITED STATES PATENT OFFICE.

JONATHAN DUNGAN, OF PROSPECT PARK, PENNSYLVANIA.

DREDGING UTENSIL.

SPECIFICATION forming part of Letters Patent No. 690,249, dated December 31, 1901.

Application filed April 5, 1901. Serial No. 54,468. (No model.)

To all whom it may concern:

Be it known that I, JONATHAN DUNGAN, a citizen of the United States, and a resident of Prospect Park, in the county of Delaware and State of Pennsylvania, have invented a new and Improved Dredging Utensil, of which the following is a full, clear, and exact description.

This invention relates to a class of utensils employed for containing and dredging all kinds of granular, ground, or powdered substances—such as salt, pepper, spices, sugar, flour, or the like—and has for its object to provide a device of the class indicated of novel simple construction and adapted for very efficient service as a dredging utensil.

The invention consists in the novel construction and combination of parts, as is hereinafter described, and defined in the appended claims.

Reference is to be had to the accompanying drawings, forming a part of this specification, in which similar characters of reference indicate corresponding parts in all the figures.

Figure 1 is a sectional side view of the device, taken through its longitudinal center. Fig. 2 is a perspective view of the dredger-body having the cap-piece removed. Fig. 3 is an inverted perspective view of the cap-piece for the dredger-box, showing features of construction on the inner side thereof. Fig. 4 is a side view of an inner lid for the dredger-body and a stirrer thereon. Fig. 5 is a plan view of the cap-piece or exterior cover of the dredger-body. Fig. 6 is a sectional side view of the upper portion of the utensil slightly modified in construction, and Fig. 7 is a sectional plan view substantially on the line 7-7 in Fig. 6.

The dredger-body 6 may be formed of any preferred material and have suitable dimensions for effective service, and, as shown, said body is a cylindrical shell closed at the bottom by a flat wall 6^a. The height of the low body 6 is proportioned to its diameter so as to adapt the utensil for convenient manipulation, and at a proper distance from the open top of the body a shoulder 6^b is formed on the exterior surface of the body by

a suitable reduction of the exterior diameter, providing a cylindrical thinner body portion

6^c, which extends from the shoulder 6^b to the upper edge of the receptacle 6.

Upon the side wall of the dredger-body 6, at or near the shoulder 6^b, a vertical rib or 55 like projection 6^d is formed to facilitate holding of the body while manipulating other parts of the device for their convenient rotative movement, as will be more fully explained. Upon the inner surface of the body 6^e 60 is a small annular flange 6^e formed, as shown in Fig. 1.

An inner cover or lid is provided for the body portion 6 and has an inverted-cup form, comprising a thin cylindrical side wall 7, 65 which has a close sliding fit within the upper portion of the parts 6 and normally seats upon the annular flange 6^e. The lid is mainly closed at the upper end of the side wall 7 by a flat or other shaped top wall 7^a, in which a 70 plurality of spaced perforations *a* are formed at a suitable distance from the side wall 7. A radial flange *b* is formed on the periphery of the top wall 7^a, which flange seats upon the free upper edge of the dredger-body 6 when 75 the inner lid is in place thereon, the outer edge of said flange then being flush with the exterior surface of the body 6, as best shown in Fig. 2.

As the improved dredger utensil may with 80 advantage be employed to sprinkle salt or powdered spices, which are liable to become lumpy or caked in the receptacle 6, it is preferred to provide a stirrer device when the device is to be employed to dredge such material, the stirrer consisting of a plurality of 85 spaced finger-pieces or rods 8, that are bunched together at their upper ends, and said ends are fixed in a depending boss 7^b, which is formed or secured on the under side of the 90 top wall 7^a at its center, as shown in Fig. 1. At diametrically opposite points two similar elongated notches *c* are formed in the radial flange *b*, the use of which will be hereinafter explained.

The outer cap-piece or cover which is provided for the utensil consists of a preferably flat or other suitably-shaped top wall 9, rounded at its outer edge and having a depending cylindrical skirt-piece 9^a formed 100 thereon at or near the periphery thereof, the length and interior diameter of the skirt-

piece being such as adapts it to slide upon and closely embrace the outer surface of the diametrically-reduced upper portion 6^c of the dredger-body 6, so as to seat upon the shoulder 6^b when all the parts of the utensil are assembled for use.

In the diametrically-reduced portion 6^c of the dredger-body 6, which extends above the shoulder 6^b, a circumferential channel *e* is formed near said shoulder and parallel therewith. At directly opposite points two vertical grooves *g* are formed in the wall of the dredger-body 6, extending from its upper edge downwardly and merging into the circumferential channel *e*, as clearly shown with regard to one of said pair of vertical grooves in Fig. 2.

On the inner surface of the top wall 9 of the outermost cap-piece or cover for the dredger-body two short lugs *h* are oppositely formed or secured and respectively occupy a corresponding notch *c* in the flange *b* on the inner lid of the utensil. A series of spaced orifices *i* is formed in the top wall 9, which orifices may be somewhat larger in diameter than that of the perforations *a* in the top wall 7^a of the inner cover for the body 6. The spaces between the orifices *i* and the relative positions of the same are similar to the spaces 30 between the perforations *a*, so that if both covers are placed upon the body portion 6 one over the other and the wall 9 is seated upon the wall 7^a and the lugs *h* occupy the notches *c* a slight rotative movement of the outermost lid or cover will be adapted to cause the orifices *i* therein to register with perforations *a* in the inner cover, and thus provide through escape-holes for the granular contents of the dredger-box when the latter 35 is inverted and shaken in the usual manner. As the notches *c* are of sufficient length to permit a partial rotation of the outermost cap-piece or cover upon the inner one and the latter cover is fitted tighter within the dredger-body than the outer one is fitted upon the exterior of said body, it will be evident that a rotative movement of the cap-piece 40 9^a on the inner cover 7^a may be readily effected to open or close the perforations in the cap-piece and cover by the manipulation of the outer cover.

To prevent an accidental displacement of the cap-piece, two small pins *m* are projected from the inner surface of the side wall 9^a opposite each other, and these pins may be entered in the upper ends of the vertical grooves *g* after the inner cover is in position on the body 6 when the notches *c* in the radial flange *b* are located over these 45 grooves, as indicated in Fig. 2, and it will be seen that if the side wall 9^a is slid down to have contact with the shoulder 6^b a rotative movement of the outer lid or cover will slide the pins *m* from the vertical grooves *g* into the circumferential channel *e*, and thus lock the outer cap-piece or cover in place; but the cap-piece or cover may be removed by re-

versing the operation that effects its locked adjustment.

It will be seen that any tendency to form lumps or caking of the contents held in the hollow body portion 6 of the improved dredger may be prevented by occasionally turning the outer cover of the device first in one direction and then in an opposite direction, which will cause the fingers 8 to break up the lumps or caked formation, reducing the salt or spice to granular form and adapting it for free sprinkling from the dredger through the orifices in the covers, which may be opened, as before explained.

In Figs. 6 and 7 the dredging device is shown slightly modified in form, the stirring-fingers 8 being dispensed with, as in the use of the device for dredging granular or powdered material not liable to become caked or lumpy the fingers are unnecessary and may be omitted. A further change consists in reversing the positions of the pins and grooves for connecting the outer lid of the dredger with the body 6. In the modified construction two opposite vertical grooves *g'* are formed in the inner surface of the side wall 9^a from its lower edge upwardly and at their upper ends merge into a circumferential groove *e'*, also formed in the inner surface of the side wall. Two short pins *m'* project oppositely from the exterior surface of the reduced upper portion of the body 6 above the shoulder 6^b and enter the groove *e'* after passing through the vertical grooves *g'*, whereby the cap-piece 9 is held rotatably but removably upon the reduced side wall 7. In the annular flange 6^e a notch *n* is formed, as shown in Fig. 6, and a mating toe *n'*, which depends from the lower edge of the depending side wall 7 of the inner lid, is adapted to occupy this notch when the inner lid is properly positioned within the upper portion of the body 6. It will be seen that the provision 115 of the interlocking toe and notch described will serve to hold the inner lid from rotation, while the outer lid is manipulated to open or close the apertures in the two lids, as before explained.

It is claimed for this utensil that it is extremely simple, dispenses with the use of screw-threads in connection of the parts, is very readily taken apart, and the parts easily reassembled for service. It protects its contents against dust, dampness, and atmospheric impurities and preserves in full strength spices, salt, or pepper placed therein.

Having thus fully described my invention, I claim as new and desire to secure by Letters Patent—

1. In a dredging utensil, a hollow body having an annular flange on its inner surface, a perforate inner lid seating on said flange, an outer cap-piece adapted to cover the inner lid, the lid and cap-piece having perforations which may be opened or closed by rotation of the cap-piece, and means for detachably holding the cap-piece on the hollow body.

2. In a dredging utensil, a cylindrical hollow body having its upper portion reduced in diameter forming a circumferential shoulder, an inner cover for the body fitting closely but 5 rotatably within said upper portion, and having a radial flange on its upper end adapted to seat upon the upper edge of the hollow body, the radial flange having opposite elongated notches therein, an outer cap-piece adapted 10 to closely but movably incase the diametrically-reduced upper portion of the hollow body, the top walls of the lid and cap-piece having like series of perforations which may be opened or closed by a turning movement of 15 the cap-piece, studs depending from the inner surface of the top wall of the cap-piece and having engagement within the notches in the radial flange, and means for detachably securing the cap-piece on the hollow body.
- 20 3. In a dredging utensil, a cylindrical hollow body having its upper portion reduced in diameter, forming a circumferential shoulder, an inner lid fitting closely within said upper portion of the body and having an opposite-notched radial flange on its upper end adapted to seat upon the upper edge of the hollow body, an outer cap-piece in inverted-cup form loosely fitting with its side 25 wall upon the reduced upper portion of the hollow body and seating on the circumferen- 30
- tial shoulder, opposite lugs on the inner side of the top wall of the cap-piece, engaging the notches in the radial flange, the top walls of the inner and outer covers having like series of perforations therein which may be opened 35 or closed by a rotative movement of the cap-piece, and a locking device on the cap-piece and the upper portion of the hollow body, adapted to removably hold the cap-piece on said hollow body. 40
4. In a dredging utensil, a hollow cylindrical body, a cap-piece thereon having a depending side wall, a pin-and-grooved detachable connection between the cap-piece and the body, an inner lid having a depending 45 circular flange, an annular rib on the inner surface of the hollow body and having a notch therein, and a toe depending from the circular flange and adapted to interlock with said notch, the inner and outer lids having perforations adapted to be brought opposite by rotatable movement of the outer lid, or to be closed by an opposite movement thereof. 50

In testimony whereof I have signed my name to this specification in the presence of 55 two subscribing witnesses.
